LIFTER FOR HARVESTERS

Charles F. Crumb and Samuel E. Hilblom, Chicago, Ill., assignors to International Harvester Company, a corporation of New Jersey

Application March 19, 1934, Serial No. 716,302

6 Claims. (Cl. 56—312)

The invention relates to a vine lifter for the guard fingers of mowers and other harvesters.

The main object is to provide such a device which will constantly be movable within limits to keep in touch with the ground notwithstanding irregularities in the contour thereof, so that the lifter will efficiently function to pick up lodged or fallen vines and grain or the like, to present such crop material properly to the cutting mechanism of the harvester and then guide the severed material over the cutting mechanism to the gathering mechanism.

Another object is to provide a lifter that will present smooth sides, and an evenly sloped upper edge, said sides and edge being unencumbered by any protuberances that would interfere with lifting and guiding the vines, etc. in a gentle manner.

Another object is to provide such a lifter that will have a body formed of sheet metal welded to a forged or cast point portion, thereby resulting in a strong, light lifter that can be cheaply produced.

Other objects will become apparent to those skilled in this art as the disclosure is more fully made.

Briefly, these desirable objects may be attained in the provision of an inverted U-shaped sheet metal body portion whose lower edges fit over the sides of a channel bar bottom portion and are welded thereto. The forward portion of the body embraces the sides of a forged or cast point and is welded thereto. The welding permits formation of smooth sides. The upper edge of the U-shaped body portion is gracefully curved upwardly and rearwardly in a manner best to perform its lifting function. This built-up, welded lifter unit is then pivotally mounted on the front end of a stub point type of guard finger, there being stops to limit the pivotal movement of the lift in opposite directions.

In the drawing:

Figure 1 is a general side elevational view of the improved lifter as it appears pivotally connected to a guard finger;

Figure 2 is a plan view of the sheet metal blank from which the main body portion is developed;

Figure 3 is a side elevational view of the point detached from the complete lifter;

Figure 4 is a detached, side elevational view of the runner or lower part of the lifter;

Figure 5 is a fragmentary plan view of the assembly, with a portion thereof in horizontal section, as seen along the section line 5—5 appearing

in Figure 1, looking downwardly, as indicated by the arrows; and,

Figure 6 is a vertical cross sectional view through the sheet metal body near its rear end to show its U-formation.

A cutter bar structure as employed in harvesters is shown at 10, the same having bolted thereto the usual series of spaced guard fingers, one of which is shown at 11. The guard finger shown is of the stub point type having a transverse hole through its front end to receive a pin 12 for pivotally mounting the improved lifter now to be described.

The body 13 of the lifter comprises a sheet metal blank, as shown in Figure 2, provided with oppositely arranged ears 14 at its widest portion, said ears having holes 15 therein. From the ears the blank is gradually tapered toward the front to form the main lifter part, while rearwardly of the ears the blank is tapered more sharply to form a tail portion 16. In back of the ears, the tail portion is formed with two holes 17.

In forming the body, the blank 13 is bent back upon itself to a U-shape, as shown in Figure 6. The narrow forward end of the body fits over the sides of the narrow rear part of a forged point 18 and is secured thereto by welding, the front edge of the sheet metal body being molecularly joined with the point at a groove 19 formed in the point for that purpose. After the point 18 has thus been secured to the sheet metal body, all protuberances are ground flush to form continuous, smooth, top and side surfaces between the point and body. The bottom of the body 13 is closed by the insertion of a channel strip 20 fitted in place as shown with the sides of the sheet metal body securely welded to the channel insert 20 at the points marked X. The rear end of the channel strip 20 is curved upwardly, as shown, to a point closely adjacent the upper edge of the body. See Figure 1.

The front end of the stub guard finger 11 includes an upstanding boss 21, which is narrower, as shown in Figure 5, than the width of the upstanding part of the channel strip 20. A pin 22 is passed through the holes 17, as shown.

In using the improved lifter in vine or other crops, the pin 12 is used to pivotally mount the lifter on the stub point of the guard finger 11, in such a manner that the upstanding boss locates between the upper stop pin 22 and the upturned end of the channel strip 20. The lifter in use, then can pivot up or down within limits, in accordance with ground irregularities. It is clear that the movement down is limited when the pin 55

22 strikes the rear side of the stationary boss 21; while the up movement is limited when the upstanding bent end of the strip 20 has its bight portion contact the front side of the stationary boss 21. The lifter along its top edge is gracefully curved from the point 18 to the end of the tail 16, said curve being upward and rearward in a manner best to lift tangled vines and the like and lift them gently, so that they can be properly cut, and thereafter to guide them back over the sickle to the gathering part of the harvester. Further, the sides of the body also are smooth and straight without any protuberances that would interfere with a smooth lifting action.

From this disclosure it will now be appreciated that an improved light weight lifter has been provided which is relatively inexpensive to manufacture, and efficient in operation.

20 It is the intention to cover all changes not departing from the spirit and scope of the invention which is defined in the appended claims.

What is claimed is:

1. A lifter adapted to be pivotally mounted on 25 a guard finger of a cutter bar, said lifter embodying a point, a body of sheet metal formed as an inverted U in cross section and presenting an open bottom edge, said body at its front end being attached to the point and increasing in depth 30 from the point to its rear end and presenting an upwardly and rearwardly curved upper edge terminating in a tail portion at its rear end, and a strip closing the open bottom edge of the sheet metal body.

35 2. A lifter adapted to be pivotally mounted on a guard finger of a cutter bar, said lifter embodying a point, a body of sheet metal formed as an inverted U in cross section and presenting an open bottom edge, said body at its front end being welded to the point and increasing in depth 40 from the point to its rear end and presenting a

smooth uninterrupted upwardly and rearwardly curved upper edge terminating in a tail portion at its rear end, and a strip closing the open bottom edge of the sheet metal body, the sides of the body having their lower edges welded to the 5 strip.

3. A lifter for a stub guard having an upwardly extending boss at its front end, said lifter adapted to be pivotally connected to the guard adjacent the lower end of the boss, said lifter having a point, a sheet metal body portion secured to the point and forming a smooth continuation thereof in an upwardly and rearwardly curved line, the body having its greatest depth adjacent the boss, a stop in the body located rearward of the boss, 10 and a strip along the bottom of the body having an upturned rear end located in front of the boss to serve as another stop.

4. A lifter for a stub guard having an upwardly extending boss at its front end, said lifter 20 adapted to be pivotally connected to the guard adjacent the lower end of the boss, said lifter having a point, a sheet metal body portion secured to the point, said body being shaped as an inverted U in cross section and presenting an open 25 bottom edge, a strip closing the bottom open edge of the body, and means to limit the up and down pivotal movement of the lifter on the guard.

5. A lifter adapted to be pivotally mounted on a guard, said lifter comprising a solid point, a 30 hollow body open at its bottom, and a strip closing the bottom, said parts being connected together by welding.

6. A lifter adapted to be pivotally mounted on a guard, said lifter comprising a solid point, a 35 hollow inverted U-shaped body connected thereto and presenting an open bottom, and a strip attached to the body and closing the bottom thereof.

CHARLES F. CRUMB. 40
